UNITED STATES PATENT OFFICE.

KARL WIESER, OF RÜTTENSCHIED, GERMANY, ASSIGNOR TO FRIED.
KRUPP, OF ESSEN-ON-THE-RUHR, GERMANY.

PERCUSSION-FUSE FOR EXPLODING SHELLS.

SPECIFICATION forming part of Letters Patent No. 750,785, dated January 26, 1904.

Original application filed September 21, 1901, Serial No. 76,019. Divided and this application filed April 22, 1902. Serial No. 104,196. (No model.)

To all whom it may concern:

Be it known that I, KARL WIESER, a subject of the Emperor of Germany, and a resident of Rüttenscheid, near Essen-on-the-Ruhr, Germany, have invented certain new and useful Improvements in Percussion-Fuses for Exploding Shells, of which the following is a specification.

This is a division of my application filed September 21, 1901, Serial No. 76,019, in which is described a percussion-fuse provided with an arrangement for so regulating the detonation of the exploding charge that it follows the ignition of the fuse with or without delay—that is to say, either at the instant the shot reaches the target or with a sufficient retardation to insure the explosion taking place during penetration or after the shot has penetrated the target—this being accomplished by having ignition transmitted either directly through non-obstructing channels, in which may be located reinforcing charges of rapidly-burning powder or causing ignition to be transmitted through a retarding charge of slowly-burning powder or the like, the adjustment of the igniting-fuse corresponding to these two results being designated for convenience as the "impact" position or the "delay" position.

The present invention constitutes a new embodiment of percussion-fuse for attaining the aforesaid object which provides for a rapid and easy changing of the condition of the fuse from delay to impact, and vice versa, by employing two controllable channels between the igniting-point and the interior of the projectile, one of which channels contains and is controlled by the retarding medium, while the other forms a by-pass around said retarding medium, so as to form a direct or immediate communication between the igniting-chamber of the percussion-fuse and the bursting charge of the shell, and is controlled by a device movable therein through the medium of which the channel may be opened or closed.

The present invention embodies as further features of improvement the specific form of device for closing the by-pass channel, as well

as the particular arrangement of reinforcing charges of rapidly-burning powder, in relation to the channels aforesaid.

The accompanying drawings, forming part of this specification, show an embodiment of the invention, by way of illustration, in its two positions or conditions of use, Figure 1 being a vertical section through the axis of the fuse and the axis of the channel forming part of the by-pass and showing the latter open, and Fig. 2 a corresponding section with the by-pass closed.

Percussion-fuses heretofore made have employed a needle-bolt A, spur-ring B, and the safety-spring C, arranged immediately in a bore of the body F and the igniting-pellet D resting in a screw-cap which closes the bore, while suitable communication is established between the igniting-chamber and the interior of the projectile. In the present invention two different passages lead from the igniting-chamber of the percussion-fuse toward the interior of the shell. One of these passages—to wit, the impact or immediate-ignition channel—is formed by an oblique channel R, extending from the igniting-chamber and terminating in a longitudinal bore S, running parallel to the axis of the fuse, extending forward to the head of the fuse-body, and receiving at its base a charge K of rapidly-burning powder, which is ignited by and reinforces the flash of the igniting-pellet, also the chamber T of the fuse-body, with which the channel S is in communication, and the longitudinal bore C of a screw-cap L, that forms the rear wall of the chamber T. Said chamber T is filled with a longitudinally and transversely bored charge K of rapidly-burning powder. The longitudinal bore in the charge K corresponds with the delay-channel, while the transverse bore corresponds with the impact or immediate-ignition chamber. The second connection or delay-channel between the igniting-chamber and the interior of the shell according to the present invention is provided by the channel U, which is filled with a retarding medium—for example, a charge N of slowly-burning powder—and

discharges into the chamber T. If the channel R, forming part of the by-pass, is open, the flash of the fuse communicates with the rapidly-burning powder K and thence to the 5 interior of the shell, and detonation of the bursting charge takes place instantly upon impact. If, however, the oblique channel R is closed, the flash from the fuse-pellet only ignites the slow-burning charge N and is communicated from the latter less rapidly to the rapidly-burning charge K through the longitudinal bore, so that the last-named charge K detonates the bursting charge only after the 10 lapse of sufficient time to permit penetration 15 to have taken place partially or wholly, according to the selection of the charge M.

The device for cutting off the channel R, which forms part of the immediate communication between the igniting-chamber of the 20 percussion-fuse and the bursting charge, consists of a device manually movable in or removable from the bore S. This may consist of a bolt V, introduced into the bore S, terminating just above the reinforcing charge K 25 and fixed in or released from the bore by screwing in or unscrewing.

When the shell is to be exploded without delay by this fuse, the screw-bolt V is removed. The fire-jet then passes through the 30 channels R, S, T, and Q and explodes the charge before the slow-fire-powder mass in the channel U is completely burned. When, however, the explosion is to be delayed and not to take place until the shell has penetrated 35 into the target, the channel S is filled up by the insertion of the screw-bolt V, so that the ignition of the bursting charge cannot take place until after the slow-fire-powder mass in the channel U has burned through to the channel T.

As may be readily seen, the above-described arrangements may also be used for such percussion-fuses as are combined with a time-fuse into a combination-fuse without materially changing the nature of the invention. 45 The closing up of the direct connection between the fire-space of the percussion-fuse and the bursting charge may also be effected by other means than those shown and described.

Having thus described my invention, the following is what I claim as new therein and desire to secure by Letters Patent:

1. A fuse for shells having two separate 55 passages, one of which is permanently open to the interior of the shell, and is provided with means for communicating ignition thereto with delay, while the other communicates ignition without delay, and means manually movable to close the passage which communicates ignition without delay.

2. A fuse for shells having two separate 60 passages, one of which is permanently open to the interior of the shell and is provided with means for communicating ignition thereto with delay, while the other communicates

ignition without delay, and means operable from the exterior of the fuse and adapted to open and close the passage which communicates ignition without delay.

3. A fuse having two separate passages, 70 between the ignition-chamber and the interior of the shell, one of which is permanently open and contains a retarding medium and communicates ignition with delay, and the other of which forms a by-pass around the retarding 75 medium and transmits ignition without delay, and means for cutting off said by-pass manually.

4. In a percussion-fuse for shells, the combination of two connections between the percussion-chamber of the fuse and the bursting charge of the shell, one of which connections is substantially direct between the said space and said charge while the other has an interposed slow-burning mass, and a screw-bolt 80 adapted for interrupting the direct connection between the fuse and the bursting charge, substantially as described.

5. A fuse having a passage communicating between the igniting-chamber and the interior 90 of the shell, a slow-burning medium interposed in said passage, a laterally-disposed bore having communication with the ignition-chamber and the interior of the shell, forming a by-pass around the slow-burning medium, and a manually-adjusted device movable in said bore, opening or closing the same, and permitting immediate transmission of the igniting-flame or causing the igniting-flame to be transmitted through the slow-burning medium, according as it opens or closes the by-pass.

6. A fuse having a passage communicating between the igniting-chamber and the interior of the shell, a slow-burning medium interposed in said passage, a laterally-disposed bore having communication with the ignition-chamber and the interior of the shell, forming a by-pass around the slow-burning medium, a reinforcing charge of rapidly-burning explosive in said laterally-disposed bore, and a manually-adjusted device movable in said bore, opening or closing the same, and permitting immediate transmission of the igniting-flame or causing the igniting-flame to be transmitted through the slow-burning medium, according as it opens or closes the by-pass.

7. A fuse having two channels forming communications between the point of ignition 120 and the interior of the projectile, a retarding medium in one of said channels, and the other channel forming a by-pass around said retarder, a chamber forming a part of both channels containing a reinforcing charge, a longitudinal bore in the reinforcing charge leading from the retarding medium, a transversely-disposed bore in the reinforcing charge forming a part of said by-pass, and means for closing said by-pass.

8. In a percussion-fuse, the combination with the primer, of two passages communicating ignition to the bursting charge, a delay-action device in one of said passages, and
5 manually-operated means movable independently of the primer to open and close the other passage.

The foregoing specification signed at Dusseldorf this 7th day of April, 1902.

KARL WIESER.

In presence of—

WILLIAM ESENWEIN,
PETER LIEBER.
